ICE MACHINE CONTROL

Edward Rodgers, Detroit, Mich.

Application December 29, 1958, Serial No. 783,492

1 Claim. (Cl. 62—137)

This invention relates to an ice machine control and more particularly to a control means which controls the feed of a bulk material, such as flaked ice, through a discharge chute.

In various types of machines which produce a bulk material which is fed out of the equipment and into carry-off receptacles or the like, it is necessary to provide a suitable control means to stop the production and delivery of the bulk material in the event that the material is not carried away from the machine at the same rate as the machine produces the material. This is particularly true in ice forming machines which are designed to produce flaked ice or the like and which deliver ice to carry-off receptacles.

While there are many types of control means available on the market today, most of them do not operate satisfactorily, and particularly, none of them operate satisfactorily in the condition of extreme cold, as is found in an ice forming machine.

Thus, it is an object of this invention to form a control for regulating or shutting off the feed of a bulk material, and particularly flaked ice or the like, where the removal of the bulk material is not rapid enough to keep up with the delivery of the bulk material.

Another object of this invention is to provide a control for a flaked ice forming machine such as the type shown in U.S. Patent No. 2,813,403 of Ostrom, issued November 19, 1957 wherein flaked ice is formed upon a stationary drum and is delivered from the machine down a discharge chute to carry-off receptacles. Having in mind such a machine, it is important to shut off the machine when the ice is not carried away as fast as it is produced, and it is important to provide a control which operates under low temperature conditions. The invention hereof, is specifically designed to operate in conjunction with such an ice forming machine of the above patent as well as with other types of bulk material delivery machines, and to operate positively and accurately regardless of the temperature conditions.

Yet another object of this invention is to form a bulk material delivering system with the control means being extremely inexpensive, formed of only a few parts, with only one of the parts moving, and being arranged to operate only when the discharge of bulk material exceeds the carry-off rate of the bulk material so that the bulk material builds up, and upon such build-up, actuates a control to stop further delivery.

These and other objects and advantages will become apparent upon reading the following description of which the attached drawing forms a part.

With reference to the attached drawings, in which:

Fig. 1 is a schematic perspective view of an ice making machine, such as is shown in the above mentioned U.S. Patent No. 2,813,403, and particularly, illustrates the novel control means.

Fig. 2 is a top view of the device shown in Fig. 1, and

Fig. 3 is a view taken in the direction of arrows 3—3

2

of Fig. 2 and shows the delivery of bulk material down the delivery chute.

Fig. 4 is a view identical to Fig. 3 but illustrates the operation of the control means due to a build-up of bulk material.

The control means hereof may be used in other types of situations, but it is particularly useful in conjunction with the ice making machine mentioned above and hence, its operation and disclosure is made in conjunction with 10 an ice machine.

In Fig. 1, the ice machine is generally designated as 10 and comprises a vertical stationary drum 11 which is refrigerated. A nozzle means 12 is arranged above the drum for spraying water upon the top of the drum. The 15 water trickles down the sides of the drum and almost immediately freezes into ice which adheres to the surface of the drum. The means for refrigerating the drum can be any of the conventional refrigeration means available on the market and since it forms no part of this invention, it is not illustrated.

The sheet of ice, which builds up upon the surface of the drum, is removed by means of a rotating cutter 14, which rotates about its own vertical axis and also rotates around the drum upon collars 13 which are arranged at 25 the upper and lower part of the drum. These collars are rotated around their own axes which are coincident with the drum axis and they, as well as the cutter 14, are caused to rotate by means of a suitable motor and gear arrangement (not illustrated).

30 As the cutter rotates about the drum, it cuts the sheet of ice off the drum and the ice is thereby formed into flakes which drop down upon a chute 16. The formation of the sheet of ice and the operation of the cutter is continuous. The chute is formed with at least part of 35 it being inclined as at 17. Hence, the flakes travel down the chute, are confined between the upturned edges 18 of the chute, and land in a suitable receptacle 20.

The operator of the machine, may then carry the receptacle away upon its being filled and substitute an 40 empty receptacle. Ordinarily, the machine runs continuously with the operator exchanging receptacles as they are filled.

At times, the operator is not available to remove the 45 receptacle or does not notice the receptacle being filled and thus, if the machine continues operation, it would deliver the flaked ice to the point where it would fall out of the receptacle and upon the floor surrounding the machine. Thus, the specific improvement herein, is a 50 control means which will shut off the icemaking apparatus when the receptacle is filled.

The control comprises a shaft 24 journaled at its opposite ends in the frame 25 which forms the support frame for the ice machine. A swingable gate 26 is fixed 55 at its upper end 27 to the shaft and is arranged transversely of the chute. This gate is preferably of a narrower width than is the chute. The lower end 28 of the gate is arranged above the level of the chute some short distance, such as a few inches, for reasons to be explained below.

60 The gate is so formed that it normally hangs vertically under the influence of gravity, but upon being pushed will swing in the direction of the receptacle about the shaft axis and will thus cause the shaft to rotate. At the end of the shaft, a suitable electrical control means, such as a conventional mercury switch 32 is rigidly secured. The switch may be of the type which closes when tilted out of a horizontal position so that rotation of the shaft causes the switch to operate. As seen in Fig. 3, the switch is connected by wires 33 to the motor M (schematically shown) which operates the standard compressor unit, which maintains the cold temperature of the drum, and

also which operates the collars and cutter and thus, shuts off the motor to stop the icemaking process.

At the side edges of the gate, a pair of baffles 29 and 30 are arranged. The baffles rise upwardly from the chute to form with the gate 26 a chamber which is opened at the end most remote from the receptacle. In operation, the ice flakes travel down the chute in the area which is free of the gate and also travels down the chute beneath the bottom edge 28 of the gate and into the receptacle. This is illustrated in Fig. 3.

When the receptacle is filled, the flakes back up the chute until the level of the bottom edge of the gate 28 is reached and thereafter, the flakes build up within the chamber formed by the baffle 29 and 30 and the gate 26 until the weight of the flakes pressing against the gate causes the gate to swing and hence causes the shaft to rotate. The partial rotation of the gate, only a few degrees, is enough to cause the switch to operate to thus shut off the motor which drives the machine.

When the flakes are removed from the chute, and particularly when the deposit built up behind the gate is removed, the gate returns to its normal vertical position and the switch again operates to turn on the motor and causes the machine to continue operation.

As can be seen, the controls herein may be useful in other places wherein a simplified form of control which will operate under almost any conditions of heat and temperature is desirable.

This invention may be further developed within the scope of the following attached claim. Accordingly, it is desired that the foregoing description be read as being merely illustrative of an operative embodiment of this invention and not in a strictly limiting sense.

I claim:

In a flake ice making machine of the type having a means for freezing water into ice and a means for form-

ing the ice into flakes and having a chute with an inclined top surface for receiving the flakes at its upper end and for discharging the flakes at its lower end into a receptacle means, the improvement comprising an on-off control means including a horizontally arranged, rotatably mounted shaft arranged transverse to, but considerably above, the top surface of the chute; a vertically arranged flat plate having its top edge fixed to the shaft and having its bottom edge arranged a short distance above the top surface of the chute, the plate being otherwise free of connections, the plate being swingable out of its vertical position around the horizontal axis of the shaft to thus simultaneously rotate the shaft about its axis, and switch means operatively connected to one end of the shaft

5 remote from the plate and being operable in response to rotative movement of the shaft and operating to turn off the machine for making flake ice when the plate is out of its vertical position only, whereby the flakes normally pass down the chute beneath the bottom edge of the plate without touching the plate, but when the receptacle means fills up, the flakes remain on the chute top surface until a deposit of flakes build up against the face of the plate which faces towards the higher end of the chute top surface and the weight of said deposit causes the plate to 10 swing into a non-vertical position to thus operate the switch means and stop the machine from making flake ice.
